UNITED STATES PATENT OFFICE.

FRANKLIN SIMON, OF NEW YORK, N. Y.

DESIGN FOR A SCARF.

58,406.

Specification for Design.

Patented July 12, 1921.

Application filed June 2, 1920. Serial No. 386,078. Term of patent 7 years.

To all whom it may concern:

Be it known that I, FRANKLIN SIMON, a citizen of the United States, residing at New York city, county of New York, and State of New York, have invented a new, original, and ornamental Design for a Scarf, of which the following is a specification, reference being had to the accompanying drawing, forming a part thereof.

The accompanying drawing is a plan view of a scarf embodying the design, spread out upon a flat surface with the middle portion of the scarf broken away.

I claim:

The ornamental design for a scarf, substantially as shown.

FRANKLIN SIMON.
